UNITED STATES PATENT OFFICE.

THOMAS R. KENNEDY, OF ROCHESTER, NEW YORK, ASSIGNOR TO THE COOPERATIVE FOUNDRY COMPANY, OF SAME PLACE.

DESIGN FOR A GRATE-FRAME.

SPECIFICATION forming part of Design No. 28,071, dated December 21, 1897.

Application filed August 23, 1897. Serial No. 649,282. Term of patent 14 years.

To all whom it may concern:

Be it known that I, THOMAS R. KENNEDY, a citizen of the United States, residing at Rochester, in the county of Monroe and State of New York, have invented and produced a new and original Design for Grate-Frames, of which the following is a specification, reference being had to the accompanying drawings, forming part thereof.

10 My present design is for a grate-frame applicable to stoves and ranges, and the leading features are the substantially open-top frame and the end plates provided with the inwardly and downwardly extending flanges.

15 In the drawings, Figure 1 is a perspective view of my design; Fig. 2, a longitudinal sectional view, and Fig. 3 an end view of the same.

Similar reference-letters in the several figures indicate similar parts.

20 A indicates the substantially rectangular

open-top plate of the grate-frame, and B the end plates extending downwardly therefrom and having the flange B' on the outer sides, waved at the lower edge, and beneath this 25 and extending downwardly and toward the center are the flanges B².

C indicate apertures in the end plates, and on the outer side plates are the vertically-extending ribs c, and beneath them the curved 30 flanges d d. The flanges d and ribs c could be dispensed with without essentially altering the design.

At one end of one of the end plates B is a vertically-extending projection or lug D. 35

I claim—

The design for a grate-frame, substantially as herein shown and described.

THOMAS R. KENNEDY.
